UNITED STATES PATENT OFFICE.

JOHN WILLIAM BELLAIRS, OF MISHAWAKA, INDIANA.

TOY VEHICLE.

1,384,738.

Specification of Letters Patent. Patented July 19, 1921.

Application filed July 17, 1920. Serial No. 396,996.

To all whom it may concern:

Be it known that I, JOHN W. BELLAIRS, a citizen of the United States, residing at Mishawaka, in the county of Saint Joseph 5 and State of Indiana, have invented a new and useful Toy Vehicle, of which the following is a specification.

This invention relates to toy vehicles, one of its objects being to provide a structure 10 of this character which affords a comfortable rest for the knee and leg of the user and which also provides a supplemental rest on which one of the knees can be placed while coasting.

15 A still further object is to provide a vehicle which can be adjusted readily to different heights, which is strong, attractive, and cannot readily get out of order.

With the foregoing and other objects in 20 view, which will appear as the description proceeds, the invention resides in the combination and arrangement of parts and in the details of construction hereinafter described and claimed, it being understood 25 that, within the scope of what is claimed, changes in the precise embodiment of the invention shown can be made without departing from the spirit of the invention.

In the accompanying drawings the preferred form of the invention has been 30 shown.

In said drawings—

Figure 1 is a side elevation of the device.

Fig. 2 is a bottom plan view thereof on 35 a reduced scale.

Fig. 3 is a rear elevation.

Referring to the figures by characters of 40 reference 1 designates the body of the vehicle preferably formed of a narrow board from one end of which depends a short block 2 supporting a longitudinal strip or reach 3 the front end of which is forked as shown at 4. The rear end of the reach is curved upwardly and rearwardly as shown at 5, 45 said curved portion being preferably concentric with the axis of a hinge 6 which is provided for connecting to the rear portion of the strip 1 a bolster 7. An opening 8 extends through the bolster and the strip or 50 reach 3 projects through this opening, there being a longitudinal series of openings 9 within the curved part 5 any one of which is adapted to receive a locking bolt or pin 10 extending transversely through the bolster. 55

The bolster is supported by wheels 11 at

the sides thereof and has laterally extending wings 12 constituting rests or supports, it being possible for the user to place one leg on one of these rests or supports while coasting. 60

Arranged in front of the strip 1 is a head 13 which can be suitably shaped and has oppositely extending grips 14. A fork 15 extends upwardly and straddles this head, the 65 fork extending from a block 16 from which projects a downwardly extending fork 17 in which is mounted a front or steering wheel 18. A series of openings 19 is formed in the fork and any one of these 70 openings is adapted to receive a holding pin 20 insertable transversely through the head.

Rearwardly extending tongues 21 are secured to the head 13 and are mounted on a pivot pin 22 which extends downwardly 75 through the front portion of the strip 1 and through the fork 15, one of the tongues 21 being arranged within the fork while the other tongue is arranged between said fork and the strip 1.

Secured on the rear portion of the strip 1 is a cushion 23 which can be of any suitable material and of any shape desired, this cushion being adapted to support one of the legs or knees of the user while the vehicle is 85 being propelled forwardly. Thus discomfort to the user is avoided.

In using the vehicle one knee is placed on the cushion 23, the two grips 14 are clasped in the hands of the user, and one foot is 90 employed for propelling the vehicle forwardly. After the vehicle has attained a desired momentum the leg which is free at the side of the vehicle can be placed on one of the rests 12 so that both feet will thus be 95 held off the ground.

It is to be understood of course that the vehicle may be made of any shape desired. In order to adjust the vehicle vertically the pin 20 can be withdrawn and the block 16 100 shifted longitudinally to a desired position after which the pin is reinserted into engagement with the fork 15. Then the pin 10 can be removed and the bolster 7 can be 105 adjusted angularly so as to lower the strip 1 from the position shown in Fig. 1. The pin 10 can then be reinserted and will enter one of the other openings 9 in the curved portion 5 of the reach.

While the cushion 23 has been shown in 110 connection with a particular form of vehicle, it is to be understood that it as well

as many of the other features of this device can be applied to other types of toy vehicles already in use.

What is claimed is:

- 5 1. A toy vehicle including a body, a cushion upon the rear portion thereof, a bolster hingedly connected to the body, a reach fixed to and extending under the body, an adjustable connection between the reach and bolster for holding said bolster at angular adjustment relative to the body, a steering head, tongues extending rearwardly from the head, a bolster hingedly connected to the body, supporting wheels connected to the bolster and steering head respectively, a reach bar adjustably and pivotally connected to the bolster and pivotally connected to one of the tongues, and a pivotal connection between the tongues and the body.
- 10 2. A toy vehicle including a body, a steering head pivotally connected to the front end thereof, a supporting wheel therefor, a bolster hingedly connected to the rear end of the body, supporting wheels therefor,
- 15
- 20

means for holding the bolster at angular adjustment relative to the body, a knee supporting cushion upon the body, and a leg rest extending laterally from the bolster.

- 25 3. A toy vehicle including a body, a steering head, tongues extending rearwardly from the head, a bolster hingedly connected to the body, supporting wheels connected to the bolster and steering head respectively, a reach bar adjustably and pivotally connected to the bolster and pivotally connected to one of the tongues, and a pivotal connection between the tongues and the body.
- 30

In testimony that I claim the foregoing as my own, I have hereto affixed my signature in the presence of two witnesses.

JOHN WILLIAM BELLAIRS.
